[57] **CLAIM**

The ornamental design for a wall oven, as shown and described.

DESCRIPTION

FIG. 1 is perspective view of a wall oven showing my ornamental design;

FIG. 2 is a front view of the wall oven of FIG. 1 showing my ornamental design;

FIG. 3 is a top plan view of the wall oven of FIGS. 1-2 showing my ornamental design;

FIG. 4 is a bottom view of the wall oven of FIGS. 1-3 showing my ornamental design;

FIG. 5 is a left side view of the wall oven of FIGS. 1-4, which forms a typical side view, showing my ornamental design, the sole difference being that this embodiment comprises a pair of oven doors;

FIG. 6 is a perspective view of a modified embodiment of the wall oven showing my ornamental design;

FIG. 7 is a front elevational view of the wall oven of FIG. 5 showing my ornamental design;

FIG. 8 is a top plan view of the wall oven of FIG. 6-7 showing my ornamental design;

FIG. 9 is a bottom view of the wall oven of FIGS. 6-8 showing my ornamental design; and,

FIG. 10 is a left elevational view of the wall oven of FIGS. 6-9, which forms a typical side view, showing my ornamental design.

The broken line showing of a wall oven is for illustrative purposes only and forms no part of the claimed design.
